3,409,648 PROCESS FOR PREPARING CARBOXYLIC ACIDS FROM OLEFINS

Roby Bearden, Jr., and Joseph Kern Mertzweiller, Baton Rouge, La., assignors to Esso Research and Engineering Company, a corporation of Delaware
No Drawing. Filed July 16, 1965, Ser. No. 472,724
11 Claims. (Cl. 260—413)

ABSTRACT OF THE DISCLOSURE

The invention is directed to an improved process for forming chiefly C_6 — C_{30} linear organic acids by first oxonating a C_5 — C_{29} alpha or internal olefin, preferably a linear olefin, selectively to aldehydes in the presence of a soluble cobalt oxonation catalyst and then contacting the aldehydes previously formed with the oxygen in the presence of the residue of the cobalt oxonation catalyst while maintaining an oxygen feed rate of at least 0.9 mole of oxygen per mole of aldehyde per unit time.

The present invention is directed to an improved process for preparing carboxylic acids from their corresponding C_n alpha or internal olefins in a two-stage oxonation-oxidation process.

More specifically, the present invention is directed to an improved process for forming C_{n+1} , e.g., C_6 to C_{30} organic acids composed chiefly of linear C_6 to C_{30} or-
ganic acids by first oxonating their corresponding C_n alpha or linear internal olefins, e.g. C_5 to C_{29} linear ole-
fins, selectively to aldehydes in the presence of a suitable oxonation catalyst; and then oxidizing, e.g., with the use of air or other suitable oxygen-containing gas, these aldehydes to acids in the presence of the cobalt from the oxonation step while feeding oxygen to said oxidation at a rate of at least about 0.9 mole of oxygen/mole of aldehyde/unit time. The present invention makes it possible to obtain high yields of substantially linear acids from their corresponding C_{n-1} olefins or mixtures of olefins by subjecting the olefins to an oxonation-air oxidation reaction sequence characterized by the use of the same cobalt catalyst (although in a different state) for oxidation of the aldehyde to the corresponding acid as was employed for the oxonation of the C_n olefins to the corresponding C_{n+1} aldehydes while insuring that the proper oxygen feed rate is maintained to insure the selectivity capable of being obtained by the present invention. One of the significant advantages of the present invention is that no cobalt removal step is required between the oxonation and oxidation sequential steps since the same reaction mixture emanating as the reaction product stream from the oxonation reaction is employed in the oxidation reaction except that instead of feeding carbon monoxide and hydrogen, air or other suitable oxygen-containing gas is fed during the oxidation step. This allows economies in the production of substantially linear C_{n+1} organic acids from their corresponding C_n alpha or linear internal olefins.

Another feature of the present invention is that we have discovered that selectivity in converting aldehydes to their corresponding acids is directly dependent on the maintenance of certain critical oxygen supply rates. This is surprising since the rate of aldehyde conversion during oxidation bears no strict relationship to the rate of oxygen supply. Thus, according to the present invention, it has been discovered that in a continuous flow operation at least approximately 0.9 mole of oxygen must be supplied per mole of aldehyde per unit time to insure high selectivities of the desired linear acids. Batch reactions in which a large excess of aldehyde was present during air oxidation gave very poor yields.

2

A wide range of alpha olefins or linear internal olefins can be employed successfully in accordance with this invention. Thus, the following olefins can be listed as exemplary of those which can be used in accordance with this invention. Suitable examples of olefins which can be selectively oxonated and then oxidized to yield the corresponding linear C_{n+1} organic acids and mixtures thereof include, but are not limited to, the following: C_5 to C_{29} alpha or internal olefins and mixtures thereof, e.g., pentene-1, hexene-1, heptene-1, octene-1, nonene-1, decene-1, undecene-1, dodecene-1, eicosene-1, docosene-1, heptacosene-1, etc. and/or the corresponding internal isomers and mixtures thereof. Suitable mixtures of alpha or linear internal olefins can be C_5 to C_{29} olefinic petroleum streams containing a predominant portion of alpha or linear internal monoolefins. Such olefins are derivable from any suitable sources, e.g. cracking of waxes or petrolylums; halogenation followed by dehydrohalogenation of paraffins; ethylene growth reactions on metal alkyls, etc. Suitable refinery streams derived from cracking wax within the C_5 to C_{29} carbon number range can have the following characteristic composition:

Olefinic components:

	Concentration (wt. percent)
C_5	0.70
C_6	5.70
C_7	6.99
C_8	6.20
C_9	8.10
C_{10}	9.70
C_{11}	8.35
C_{12}	5.55
C_{13}	7.10
C_{14}	7.10
C_{15}	8.90
C_{16}	5.80
C_{17}	5.80
C_{18}	3.50
C_{19}	
C_{20}	
Bottoms	10.51

The oxonation step, whereby the alpha or linear internal olefins or mixtures thereof are converted to their C_{n+1} corresponding aldehydes can be conducted readily in the presence of paraffinic solvents within the C_5 to C_{10} range. Of course, no solvent need be employed.

This oxonation reaction can be conducted at temperatures of about 150 to about 350° F., usually is conducted at temperatures of about 150 to 250° F., and preferably at temperatures of about 180 to about 220° F. in the presence of a suitable oxonation catalyst, such as a cobalt soap or dicobalt octacarbonyl; but any suitable oxonation catalyst capable of selectively converting the olefins to their corresponding C_{n+1} aldehydes can be employed.

The oxonation reaction is conducted for a sufficient period of time to substantially oxonate most of the olefins present in the feed stream to aldehydes. This time can vary widely, depending upon the specific reaction temperature, reaction pressure, olefins present in the feed stream, etc. However, in the case of a cobalt octacarbonyl catalyst employed in conjunction with C_6 to C_{26} alpha olefins (>90 wt. percent of the feed stream being said alpha olefins) and when the oxonation temperature is 180 to 220° F. and when synthesis gas pressure is 100 to 150 atmospheres, oxonation can be conducted satisfactorily in a 60 to 180 minute reactor holding period. The lower temperatures and pressures are preferred as this favors linear aldehyde formation.

Carbon monoxide and hydrogen (synthesis gas) are fed to the oxonation reaction zone to supply the requisite

3

materials for the aldehyde synthesis reaction; normally a considerable excess of both CO and H₂ are used. Thus, a carbon monoxide is usually supplied to allow 2-20 moles of carbon monoxide per mole of olefin present in the feed stream per unit time. Preferably, the carbon monoxide feed rate is 5 to 10 moles of carbon monoxide per mole of olefin per unit time. Hydrogen can be fed at a feed rate of 2 to 20 moles of hydrogen per mole of olefin per unit time. Usually, the hydrogen feed rate ranges from about 5 to 10 moles per mole per unit time. Normally the consumption ratio of H₂/CO is very near the theoretical 1/1 volume ratio for aldehyde synthesis; hence the mixed gases are best fed in this composition. In either batch or continuous oxonation processes, a continuous flow of the gas mixture is a convenient method of maintaining the gas composition essentially constant. The pressure in the oxo reaction stage is normally in the range of 50 to 300 atmospheres, preferably 65-200 atmospheres.

Subsequent to the oxonation step described above, the oxo reaction product, including the soluble cobalt octacarbonyl or other suitable oxonation catalyst, is discharged at a controlled rate from the oxonation reactor or other storage vessel into the oxidation reactor vessel, which can be a glass reactor equipped with appropriate agitation devices, such as a stirrer, and appropriate facilities for the feeding of the oxygen-containing gas thereto. The rate at which the oxygen is fed to the oxidation reaction zone is controlled by any suitable gas feeding and regulator device to insure that the proper concentration of oxygen with respect to aldehyde is maintained during the oxidation stage.

According to the present invention, at least 0.9 mole of oxygen per mole of aldehyde present in the oxo reaction product per unit time must be supplied in order to obtain the selectivity of reaction which the present invention is capable of attaining. Usually, the oxygen feed rate in a continuous flow operation ranges from about 0.90 to 3.2 moles of oxygen per mole of aldehyde per unit time, and preferably from 0.9 to 1.2 mole/mole/unit time. Thus, according to the present invention, it has been discovered that use of oxygen supply rates below 0.9 mole/mole/unit time usually results in far inferior selectivities and acid yields. Thus, when the oxygen supply rate (oxygen feed rate) was reduced from 1.2 to 0.60 mole/mole/hr. in an oxidation stage having the same n-cobalt catalyst and conducted in the presence of n-heptane using the same weight concentration of catalyst at the same oxidation temperatures, the 0.6 mole/mole/hour run resulted in an acid yield of 65.5 mole percent aldehyde present in the oxo reaction product feed stream to the oxidation step versus a 80.6 mole percent acid yield when the oxygen feed rate was 1.2 mole/mole/hour.

Characteristically, the oxidation stage of the present invention can be conducted at temperatures of about 0 to about 212° F., usually at temperatures of about 32 to about 160° F., and more preferably at temperatures of about 86 to about 122° F. One to 50 atmosphere pressure can be used for oxidation, but usually the pressure maintained during the oxidation step ranges only slightly above atmospheric, e.g., 2 to 4 p.s.i. above atmospheric pressure. However, oxidations carried out at elevated pressure would increase the solubility of oxygen in the reaction solvent, hence providing even more favorable oxygen to aldehyde ratios with improvements in acid yield. Within the purview of this invention the oxidation reaction takes place essentially instantaneously so that reactor holding time is not a vital consideration.

Usually the catalyst is employed in the oxonation (1st stage) step in concentrations ranging from about 0.05 to 0.5 wt. percent cobalt catalyst (as cobalt metal based on olefins) present in the predominantly olefinic feed stream to the oxonation step. Preferably, the catalyst concentration on this basis ranges from about 0.1 to 0.2

wt. percent. Essentially none of this catalyst is lost during the transfer from the oxonation vessel to the oxidation vessel, hence essentially the same catalyst concentration is present during the oxidation step as was present during the oxonation step. As soon as the oxygen is fed to the reaction products from the oxonation step, aldehyde oxidation to the corresponding organic acid, or mixtures thereof, takes place almost immediately. Thus, e.g. the dicobalt octacarbonyl oxonation catalyst from the oxonation step is used directly and converted in situ directly to the active cobalt oxidation catalyst.

An interesting and advantageous advantage of the present invention is that there appears to be a built-in refining feature which is a concomitant advantage. This built-in advantage is that the branched isomeric aldehydes present in the oxonation reaction product are at least partially converted during the oxidation step to readily separable materials when the oxidation step is conducted using the above-mentioned critical oxygen feed rates. Thus, the branched aldehydes undergo reaction to make high molecular weight oxygenated compounds free of carboxyl groups. These high molecular weight oxygenated compounds are high boiling, and are not soluble either in water or alkaline medium so that they are readily separable from acid products. This results in higher concentrations of linear acids in the composition of the acid product stream obtained after separation of the acids from the oxidation reaction products.

Subsequent to the oxidation step, the (linear) acid containing products stream can be decobalited to remove essentially all of the cobalt oxonation-oxidation catalyst therefrom using any suitable decobalting procedure. The recovered catalyst can then be treated to reactivate its capacity for further use.

After the decobalting of the oxidation reaction products stream has been conducted, these acid products are then extracted by treatment of the reaction products stream with a dilute sodium hydroxide-aqueous solution to separate the impurities and materials which are insoluble in water and alkali therefrom. Usually the aqueous sodium hydroxide solution contains from 5 to 25 wt. percent sodium hydroxide and more preferably from about 5 to about 10 wt. percent thereof. Then the (linear) acid product stream can be further purified by flash distillation to remove the insolubles followed by liberation of the raw product acids by addition of a suitable acid thereto, e.g. dilute hydrochloric acid. It is also within the scope of this invention to separate and purify the acids by other suitable means, e.g. distillation, selective extraction, etc.

The present invention will be illustrated in further detail by the following examples.

Example 1

A mixture of 273.5 g. (3.25 moles) of hexene-1 and 11.4 millimoles of preformed cobalt octacarbonyl in heptane (35 g. of solution) was charged to a 1-liter stainless steel autoclave. Oxonation was then begun at a synthesis gas pressure of 1800 p.s.i.g. and at 212° F. using a synthesis gas blend containing a mole ratio of H₂ to CO of approximately 1.3:1. After 5 hours the uptake of synthesis gas had ceased and the reactor product, 416 g., was discharged. Analysis by gas chromatography showed a 95% yield of aldehyde product with 81% selectivity to the linear aldehyde.

Next, a mixture of 28 g. of the oxo product and 300 ml. of n-heptane was charged to a glass reactor equipped with stirrer and air inlet tube (frit). Dry air was passed into the mixture at 104° F. until the characteristic green color of the active cobalt oxidation catalyst occurred (7 minutes) and until ΔV measurements on the exit air indicated that oxygen was no longer being consumed, i.e. the initial aldehyde charge had been used up. At this point the remainder of the aldehyde charge, 172 g., was fed to the reactor at a rate of 0.1 mole aldehyde per hour. The

air rate was regulated to supply 0.32 mole O_2 per hour. After 312 minutes the reaction was no longer exothermic, and the temperature began to drop from the 104° F. mark held previously by means of an ice bath. At 360 minutes there was no further uptake of oxygen and the reaction was terminated. Cobalt catalyst was then removed. The acid products were then extracted into a 10% sodium hydroxide in water solution. Traces of hexane and alkaline insoluble by-products were removed from the alkaline extract by flash distillation (steam) and the crude acids were liberated by adding dilute hydrochloric acid. There was obtained 153 g. (75 mole percent based on olefin) of carboxylic acids. Linear acid content was determined by gas chromatography to be 86%.

Example 2

After conducting the oxonation reaction employing a C_8 refinery alpha olefin feed containing chiefly octene-1 and reaction conditions indicated in Example 1 above, an oxidation stage was conducted at 104° F. using n-heptane as solvent and employing a catalyst concentration of 0.2 wt. percent cobalt. These runs were conducted to study the effect of oxygen feed rate variation upon selectivity as demonstrated by yield of acids. Table I below summarizes the data obtained from four runs including a batch reaction (Run 1) and three continuous flow runs (Runs 2-4) wherein the aldehyde feed rate from the oxonation reaction to the oxidation step was controlled at 0.1 mole of aldehyde per hour. The pertinent data are tabulated herein below in Table I.

TABLE I.—VARIABLE STUDIES— C_8 ALDEHYDE AIR OXIDATION
(Oxidation Temp.: 104° F.; Catalyst: 0.2 Wt. Percent Cobalt; Solvent: n-Heptane)

Run No.	Aldehyde Feed Rate, Moles/Hr.	Ald. Conv. Rate, Moles/Hr.	Oxygen Feed Rate, Moles/Hr.	Oxygen Use Rate, Moles/Hr.	Overall Acid Yield, Mole Percent	Oxidation Yield, Mole Percent	
						Linear	Iso
1	(¹)	0.07	0.32	0.03	51.0	57.6	
2	0.1	0.08	0.06	0.06	58.0	65.5	
3	0.1	0.09	0.12	0.09	71.5	80.6	
4	0.1	0.10	0.32	0.09	73.0	82.4	

¹ Batch Reaction 0.1 Mole Ald.

Example 3

A continuous flow, oxonation-oxidation synthesis was conducted in accordance with the procedure of Example 2 above at oxygen feed rates (in air) of 0.32 mole of oxygen per mole of aldehyde per hour using an aldehyde feed rate of 0.10 mole of aldehyde per hour and a temperature of 104° F. during the oxidation (2nd stage) step. The catalyst concentration during the oxidation was 0.2 wt. percent cobalt as derived directly from the oxonation step. The four runs illustrated in this example demonstrate that instead of employing an essentially pure paraffin as the oxidation reaction solvent, the oxidation reaction product(s) from previous oxidation run(s), can be added to and employed in admixture with the paraffin solvents. Table II below illustrates a preferred embodiment of this invention where various acid containing oxygenated products are employed in mixture with n-heptane in the varying indicated weight percent mixtures. Table II below summarizes the data obtained.

TABLE II.—DILUENT STUDY— C_8 ALDEHYDE AIR OXIDATION

[Catalyst: 0.2 Wt. Percent Cobalt from the Oxidation Step; O_2 Feed Rate (in air): 0.32 mole/hr.; Aldehyde Feed Rate: 0.10 mole/hr.; Run Temp.: 104° F.]

Run No.	Acid Yield, Mole Percent	Diluent Composition, Wt. Percent	
		Heptane	Oxygenated Products
5	72.0	90	10
6	70.8	86	14
7	71.5	80	20
8	73.0	75	25

As is indicated by the above data in Table II, according to a preferred embodiment of the present invention, the crude reactor product from the oxidation step can be recycled for use as a portion of the oxidation solvent to replace some or all of the paraffinic or other oxidation sol-

vent, thereby resulting in economies with respect to the solvents employed in the oxidation stage of the present invention.

Example 4

This example illustrates the built-in refining procedure whereby the branched isomeric aldehydes emanating from the oxonation stage are converted preferentially during oxidation to alkaline insoluble materials thus facilitating recovery of higher concentrations of the desired linear acids during the oxidation stage when the latter is conducted in accordance with this invention. Runs 9 through 12 as indicated in Table III were conducted according to the procedure of Example 1, but using varying alpha olefin feeds containing from 6 to 12 carbon atoms thereby resulting in production of linear acids having from 7 to 13 carbon atoms as noted in Table III. The aldehyde composition (feed stream to the oxidation step) with respect to linear and iso aldehydes is shown in Table III along with the acid composition (after oxidation of the aldehydes to their corresponding acids has taken place). The pertinent data are tabulated in Table III below.

TABLE III.—LINEAR CONTENT OF ACIDS

Run No.	Aldehyde	Aldehyde Com- position		Acid Composition	
		Linear	Iso	Linear	Iso
9	C_7	72	28	82	18
10	C_7	81	19	84	16
11	C_9	75	25	80	29
12	C_{13}	64	36	66	34

Thus, according to the present invention, there is an inherent advantage in the quality (purity) of the linear acids obtained due to the built-in refining procedure obtained due to the conversion of branched isomeric aldehydes preferentially to alkaline insoluble materials during the second stage (oxidation) step of the present invention.

What is claimed is:

1. A process for preparing carboxylic acids from C_5 to C_{29} olefins which comprises (a) contacting said olefins with carbon monoxide and hydrogen at temperatures of about 150 to 350° F. in the presence of a dicobalt octacarbonyl catalyst for a sufficient period of time to convert said olefins to their corresponding aldehydes, and (b) contacting said aldehydes with oxygen in the presence of a catalyst consisting essentially of the residue of the dicobalt octacarbonyl catalyst employed in the formation of said aldehydes at temperatures of about 0 to 212° F. while maintaining an oxygen feed rate of at least 0.9 mole of oxygen per mole of said aldehydes per unit time to produce the corresponding carboxylic acids.

2. A process for preparing chiefly linear acids from a hydrocarbon feed stream comprised chiefly of C_5 to C_{29} linear olefins which comprises (a) contacting said feed stream with carbon monoxide and hydrogen at temperatures of about 150 to 350° F. in the presence of a dicobalt octacarbonyl catalyst for a sufficient period of time to convert said olefins to their corresponding aldehydes, and (b) contacting said aldehydes with oxygen in the presence of a catalyst consisting essentially of the residue of the dicobalt octacarbonyl catalyst employed in the formation of said aldehydes at temperatures of about 0 to 212° F. while maintaining an oxygen feed rate of at least about 0.9 mole of oxygen per mole of aldehydes per unit time to produce the corresponding linear acids.

3. A process as in claim 2 wherein said oxygen in (b) is supplied as air at an oxygen feed rate of about 0.90 to about 3.2 moles of oxygen per mole of aldehydes per unit time.

4. A process as in claim 2 wherein the oxidation step (b) is conducted in the presence of a solvent comprised chiefly of n-paraffins and crude oxidation reaction product from oxidation reaction (b).

5. A process as in claim 2 wherein said linear olefins are predominantly alpha olefins.

6. A process as in claim 8 wherein the oxidation step (b) is conducted in the presence of a solvent containing oxygenated products.

7. A process as in claim 8 wherein the oxidation step (b) is conducted in the presence of a paraffin-containing solvent.

8. A process for preparing chiefly linear acids from C₅ to C₂₉ linear olefins which comprises (a) contacting a hydrocarbon feed stream comprised chiefly of C₅ to C₂₉ linear alpha olefins with carbon monoxide and hydrogen at a temperature of about 150 to 250° F. in the presence of a dicobalt octacarbonyl catalyst for a sufficient period of time to convert said olefins to their corresponding aldehydes, and (b) contacting said aldehydes with oxygen in the presence of a catalyst consisting essentially of the residue of the dicobalt octacarbonyl catalyst employed

5 in the formation of said aldehydes at temperatures of about 32° to 160° F. at pressures ranging from about 1 to 50 atmospheres while maintaining an oxygen feed rate of about 0.90 to 3.2 moles of oxygen per mole of aldehyde per unit time.

9. The process of claim 1 wherein the oxygen-aldehyde contacting is conducted in a continuous flow operation and the oxygen feed rate ranges from about 0.90 to 1.2 moles of oxygen per mole of aldehyde per unit time.

10. The process of claim 2 wherein the aldehyde contacting is conducted in a continuous flow operation and the oxygen feed ranges from about 0.9 to about 1.2 moles of oxygen per mole of aldehyde per unit time.

11. The process of claim 8 wherein the oxygen aldehyde contacting is conducted in a continuous flow operation and the oxygen feed ranges from about 0.9 to about 1.2 moles of oxygen per mole of aldehyde per unit time.
